UNITED STATES PATENT OFFICE.

HERBERT E. BRIDGWATER, OF SYRACUSE, NEW YORK, ASSIGNOR TO REMINGTON TYPE-WRITER COMPANY, OF ILION, NEW YORK, A CORPORATION OF NEW YORK.

TYPE-WRITING MACHINE.

1,308,328.

Specification of Letters Patent.

Patented July 1, 1919.

Application filed March 28, 1918 Serial No. 225,272.

To all whom it may concern:

Be it known that I, HERBERT E. BRIDGWATER, citizen of the United States, and resident of Syracuse, in the county of Onondaga and State of New York, have invented 5 certain new and useful Improvements in Type-Writing Machines, of which the following is a specification.

My invention relates to means for guiding type bars or carriers of typewriter or like machines to a common printing center.

Difficulty has been found heretofore in providing highly efficient guiding means of the character specified. Attempts to provide 15 means for accurately guiding the type bars usually resulted in the bars sticking in the guides, thus resulting in great annoyance to the operators and loss of much time in releasing the sticking bars, readjusting the 20 carriage, etc. In some instances the constructions were such that very small guiding surfaces were presented and very slight wear would soon render them inefficient. In 25 other instances means were devised for guiding the type bars against lateral deflection but no means were provided to prevent a deflection of the type bar in the direction of its length. It has been proposed to employ roller guides to overcome some of these difficulties, the rolling contact faces of the 30 guides distributing the wear over greater surfaces and also rendering the bars less liable to stick in the guides. In no instance, however, so far as I am aware, have rolling 35 guide surfaces been employed to prevent a longitudinal as well as a lateral deflection of the type bars.

One of the main objects of my invention, generally stated, is to provide simple and 40 highly efficient type bar guiding means which may be produced at small cost and by which the disadvantages pointed out above may be overcome.

To the above and other ends which will 45 hereinafter appear my invention consists in the features of construction, arrangements of parts and combinations of devices set forth in the following description and particularly pointed out in the appended 50 claims.

In the accompanying drawings, wherein I have shown only so much of one form of typewriting machine as may be necessary to illustrate my invention in its embodiment 55 therein, and wherein like reference

characters indicate corresponding parts in the different views,

Figure 1 is a fragmentary side view partly in section of a type bar segment with several type bars and the type bar center guide 60 mounted thereon.

Fig. 2 is a fragmentary rear elevation of the same, showing but a single end type bar.

Fig. 3 is a view similar to Fig. 1, except that but one type bar is shown, and the center guide appears in side elevation, whereas 65 the segment is shown in section.

Fig. 4 is an enlarged detail front elevation of the center guide shown attached to the segment.

Fig. 5 is a fore-and-aft vertical sectional view of the same taken on the line $x-x$ of Fig. 4 and looking in the direction of the arrows at said line.

Fig. 6 is a rear elevation partly in section 75 of the same, the section being taken on the line $y-y$ of Fig. 5 and looking in the direction of the arrows at said line.

Fig. 7 is an enlarged detail fragmentary sectional view of one of the type bars at 80 the left-hand side of the system as viewed from above when near the printing point, the section corresponding to the line $z-z$ in Fig. 12 and looking in the direction of the arrows at said line.

Fig. 8 is a corresponding view of the center type bar.

Fig. 9 is a corresponding view of one of the type bars at the right-hand side of the system.

Fig. 10 is a developed plan view showing the forward ends of one-half of the system of type bars.

Fig. 11 is a diagrammatic front elevation showing the two extreme side type bars 95 and the center type bars as they appear at the printing point.

Fig. 12 is an enlarged detail diagrammatic side elevation partly in section and showing an end portion of one of the center type 100 bars and extensions in dotted lines of the guide surfaces on the bar as seen from the side.

Fig. 13 is an enlarged detail diagrammatic top plan view showing extensions in dotted 105 lines of the guide surfaces on two side bars and the center bar and how such surfaces contact with the center guide.

In the present instance I have shown my invention embodied in a well-known style of 110

front strike typewriting machine. It should be understood, however, that the invention may be incorporated in various styles of typewriting or like machines and is in no 5 sense restricted to its use in the machine of the character shown.

In the present instance a series of segmentally arranged type bars 1 are mounted to move upwardly and rearwardly to printing 10 position and to strike against the front face of the platen 2 mounted in a carriage (not shown) to travel from side to side of the machine over the top plate thereof. The type bars are mounted on a pivot wire 3 carried 15 by a type bar segment 4, the heels of the type bars working in guide slots 5 which extend through the lower edge of the segment. The type bars as they approach the 20 sides of the system are bent laterally at the end portions thereof as best shown in Fig. 10, the line of the bend in each bar being indicated at 6. From an inspection of Figs. 1 and 11 it will be understood that the body 25 portions of the type bars converge at a point coincident with the lines 6 of the bends therein when the type bars are in printing position, the printing point 7 being above and not at the point of convergence of the 30 bars. The construction is such therefore that end portions 8 of all of the type bars, which carry the type blocks 9, are adapted to be brought to the same vertical plane when the bars are in the printing position as will be understood from a consideration of Fig. 35 11. There is nothing unusual in this construction but it is pointed out in detail herein in order that there may be a better appreciation of what is to follow.

40 Any suitable means may be employed for actuating the type bars and for effecting a relative ease shifting movement between the platen and type bars.

A center guide, which is designated as a 45 whole by the reference numeral 10, is fixed in the path of all the type bars and co-acts therewith at the portion 8 of each bar which is beyond the line 6 thereof, or beyond that portion of the bar which is coincident with 50 the point of convergence of the bars. Within the broader aspects of my invention this center guide may be variously formed, many widely divergent forms of construction having been devised by me but it will suffice to 55 describe in detail the form shown in the accompanying drawings.

In the present instance roller guide surfaces which co-act with each type bar are formed on a single center guide roller, 60 though from certain aspects of my invention it is not necessary that such surfaces be formed on a single guide roller.

The center guide roller is designated as a whole by the reference numeral 11, and is

formed in the present instance with trunnion-like cone pivots 12 at the ends thereof. These pivots bear against the rounded corners 13 of bearings formed in two bracket-like supporting arms 14 and 15 between which the roller is received and by which it 65 is supported horizontally in position. The axis of the roller therefore extends transversely of each type bar when the latter is in the printing position. The arms 14 and 15 constitute members of a two-part bearing 70 or support, the members of which are united for relative adjustment and which are provided with means whereby the support in its turn may be rigidly connected to a relatively fixed support, such as the type bar 75 segment 4. Thus, from an inspection of Figs. 4, 5 and 6 it will be seen that the member 15 has two semi-cylindrical bearing members 16 which are received in corresponding seats 17 in the member 14. This 80 enables the member 15 to receive a slight swinging or pivotal movement on the member 14, the inner face of the part 15 being inclined in opposite directions, as indicated at 18, to facilitate such movement. 85 The effect of this movement of the member 15 is to bring the upper ends of the two arms and the bearings 13 therein closer together or to move them further apart as the case 90 may be. This relative adjustment between 95 the bearing arms enables the roller to be properly maintained in its centered position, free from lost motion at the bearings and to take up any such lost motion which might occur as a result of wear on the bearings. 100 Means for uniting the two members 14 and 15 and for effecting the above described adjustment will now be set forth.

A centrally disposed headed screw 19 extends through transverse openings 20 and 21 in the stems of the members 15 and 14 respectively. The axis of the screw 19 passes through the axis of the bearings 16 so as to enable an adjustment of the member 15 to be effected. It will be observed 105 moreover that the walls of the opening 20 slope outwardly from the screw and from the inner face of the member 15, so that the screw 19 passes freely through the opening 20 and when backed up offers no obstruction to the above described adjustment 110 of the member 15. The screw 19 passes transversely through the members 14 and 15 and centrally between the bearings 16 and seats 17 and is threaded into the opening 21 which is tapped to receive it. Above 115 and below the screw 19 are screws 22 and 23 respectively. These last mentioned screws are received in tapped openings in the member 15 and bear at their inner ends 120 against the inner face of the member 14, one above and the other below the pivotal axis of the member 15. When the screw 19

is loosened slightly a backing-up of the screw 22 and a threading in of the screw 23 will bring the bearings 13 of the roller closer together, whereas a reversal in the movement of the screws 22 and 23 causes a relative movement of the bearings 13 away from each other. After the desired adjustment has been attained the screw 19 may be tightened and the parts will be firmly held in such position, all three screws contributing to this end. The stem of the member 14 is extended below the member 15 and is provided with openings to receive headed screws 24, the stems of which pass freely therethrough and engage at their threaded ends in tapped openings of the type bar segment 4, or some other suitable point of support.

The guide roller 11 in the present instance is formed with a substantially V-shaped peripheral groove 25, the side walls of which form oppositely inclined guide surfaces 26 with which corresponding guide surfaces on each type bar co-act. Thus, it will be seen that each type bar is formed with a transverse slot 27 in the front edge of the portion 8 thereof. This slot is open at the forward end, or at the front edge of the bar, and extends transversely of the bar from side to side thereof. The wall of the slot nearest the end of the bar is formed with oppositely inclined guide surfaces 28, which match the guide surfaces 26 on the roller 11 in a line contact with the latter, as shown in Fig. 6. The opposite wall of the slot 27 also is formed with oppositely inclined guide surfaces 29, which likewise match in a line contact with the guide surfaces 26 on the guide roller. From an inspection of Figs. 6 and 12 it will be understood that the guide surfaces 28 and 29 on each type bar co-act with the guide roller on opposite sides of the pivotal center thereof, thus preventing displacement of the bar relatively to the guide in up and down direction or longitudinally of the type bar, whereas the guide surfaces 26 engage each type bar on opposite sides thereof and prevent any lateral deflection of the bar. Each bar therefore has an interlocking engagement with the guide roller and is guided against deflection in two directions at right angles to each other, and is compelled to move in a true course to the printing point.

It will be seen that the surfaces 28 and 29 engage the roller and remain in engagement therewith with a line contact at four points throughout a considerable portion of the final movement of the type bar to the printing position and efficiently and accurately guide each bar in a like manner to the printing position.

In order to have the guide surfaces on each type bar co-act with the guide roller in the manner described the guide surface

on each bar is formed on an arc of which the pivot of the type bar is the center. This I have attempted to illustrate in Figs. 7, 8, 9, 12 and 13. While these views are diagrammatic in character, and the proportions 70 may not be entirely accurate, they will nevertheless serve to illustrate the point in question. Referring first to Fig. 12 it will be understood that the type bar illustrated is supposed to be one near the center of the 75 system. It will be observed from the dotted lines extending from the surfaces 28 and 29 that each of these surfaces is formed as an arc, the center of which is the pivotal center of the type bar shown. These surfaces are 80 not alike on any two type bars. They differ as the angular relation of each type bar in the system differs from that of all others. Thus, in Fig. 13 I have attempted to show in dotted lines an extension of the guide surfaces 29 of, say, the extreme side type bars and the center bar, as the parts are viewed from above. Assuming for the moment that the type bar shown in Fig. 12 is the center bar, and is the same bar that is shown at 90 the center in Fig. 13, then the surfaces 29 would be formed as represented in Figs. 8, 12 and 13 in the arcs shown by the dotted line projections of said surfaces in the two last mentioned figures. As we approach 95 either side of the system of type bars from the center, however, the arc-like formation of a guide surface on each type bar becomes more inclined, the plane thereof conforming to the angular position of the type bar in the 100 system. This I have attempted to show in Fig. 13 in which it will be seen that each of the two extreme type bars of the system as it swings in from a side of the segment, has the guide surface 29 formed somewhat as 105 I have attempted to illustrate it by dotted lines in Fig. 13. In every instance, however, each of the surfaces 28 and 29 on a type bar, no matter where it may be situated in the system, will be formed on an arc of 110 which the pivot of the type bar is the center. But the relation of the guide surfaces on each type bar to the bar on which they are formed, will vary throughout the system. This I have attempted to illustrate by the 115 exaggerated showing in Figs. 7, 8 and 9 in which the showing corresponds to a section of the bar taken on the line z-z of Fig. 12 and looking in the direction of the arrows at said line. Moreover, each of Figs. 7, 8 and 9 shows a bar as seen from above and as it would appear in the printing position.—Fig. 7 may be taken to represent the extreme left-hand bar; Fig. 8 the center bar; and Fig. 9, the extreme right-hand bar. 120 These bars may be said to represent the extreme differences in the relation of the guide surfaces on the type bars. The inclination of the planes of the arcs on which the surfaces are formed will be gradually less from 125 130

the sides of the system to the center where the arc is in a vertical plane as indicated in Figs. 8, 12 and 13, and supposing for the moment the bar shown in Fig. 12 to be the center bar. With the guiding surfaces on the type bars formed in this manner such surfaces are capable of accurately co-operating with the center guide to properly direct each bar to the printing position without undue friction or cramping between any type bar and the center guide and without liability of any of the bars sticking in the guide. From an inspection of Fig. 6 it will be seen that it is only the guide surfaces 28 and 29 on each bar that co-act with the roller, the surfaces 27^a on each bar being maintained free from contact with the guide roller at all times.

The use of efficient type bar guiding means of the character shown and described herein is rendered possible by my invention of a process and machine by which the guide surfaces on the type bars are formed, and which constitute the subject-matter of a separate application Serial No. 232,247 filed by me on the 3rd day of May, 1918. By such process and machine the guide surfaces on each type bar are cut or formed while the type bar describes a movement corresponding to its printing movement in the typewriting machine and by a tool or cutter which has surfaces that correspond in form and location to the guide surfaces on the center guide. It will be readily understood therefore that while the relation of the guide surfaces on each type bar differ from those of every other bar, nevertheless, these guide surfaces may be formed in a simple manner with great accuracy and that each type bar may be directed with deadly accuracy to the printing point.

Moreover, the construction provides rolling guide surfaces which reduce the liability of the type bars to stick in the guide and distribute the wear on the center guide around the entire surface of each guide face 26, different portions of the surfaces 26 being presented for use at successive operations of the type bars. On the other hand the wear on the type bars is of course distributed between all of the type bars of the system, or say, some forty-two bars, and the character of the guide surfaces on each bar is such that the wear is distributed throughout the entire extent of each guide surface 28 and 29 notwithstanding that each at a given instant receives only a line contact on the roller. While each bar is effectively guided to the printing position there is nevertheless little resistance offered by the center guide to the printing movement of each bar, and little liability of the bars to stick in the guide.

So far as I am aware I am the first to provide a center guide equipped with rolling guide surfaces which coact with a type

carrier to guide and prevent a deflection thereof in two directions at right angles to each other.

One of the characteristics of such a construction is the provision of guide surfaces on the type bars of such a character that the relation of such surfaces on each bar shall be different from that of every other bar of the system. Notwithstanding this the guide surface on each bar is formed on an arc the center of which is the pivot of the bar. I believe that I am the first to provide such a construction and the first to provide means whereby the adoption of such a construction is rendered possible or feasible. It should be understood therefore that from the broader aspects of my invention the construction shown illustrates but one of the many forms in which my invention may be clothed and that widely divergent changes may be made within the scope of my invention.

What I claim as new and desire to secure by Letters Patent, is:

1. In a typewriting machine, the combination of a series of type bars which strike at a common center, and guiding means which guide and prevent a deflection of each bar in two directions at right angles to each other, said means comprising a center guide near the printing point and having rolling guiding surfaces with which each type bar coacts with an interlocking engagement as it approaches the printing position thus preventing a longitudinal as well as a lateral deflection of each type bar.

2. In a typewriting machine, the combination of a series of type bars which strike at a common center, and guiding means which guide and prevent a deflection of each bar in two directions at right angles to each other, said means comprising a center guide near the printing point and having rolling guiding surfaces with which each type bar coacts with an interlocking engagement as it approaches the printing position thus preventing a longitudinal as well as a lateral deflection of each type bar, the guiding surface on each bar being formed on an arc the center of which corresponds to the pivot of the type bar.

3. In a typewriting machine, the combination of a series of type bars which strike at a common center and converge near the printing point, said bars as they approach the sides of the system being bent laterally at the ends thereof beyond the point where they converge so that the end portions of all of the bars may be brought to the same plane, and guiding means which guide and prevent deflection of each bar in two directions at right angles to each other, said means comprising a center guide having rolling guiding surfaces which co-act and interlock with those portions of the type bars which are brought to the same plane and prevent a

longitudinal as well as a lateral deflection of the type carrying end portion of each bar.

4. In a typewriting machine, the combination of a series of type bars which strike at a common center and converge near the printing point, said bars as they approach the sides of the system being bent laterally at the ends thereof and beyond the point where they converge so that the end portions of all of the bars may be brought to the same plane, and guiding means which guide and prevent deflection of each bar in two directions at right angles to each other, 10
- 15 said means comprising a center guide having rolling guiding surfaces which co-act and interlock with those portions of the type bars which are brought to the same plane and prevent a longitudinal as well as a lateral deflection of the type carrying end portion of each bar, the guiding surface on each bar being formed on an arc the center of which corresponds to the pivot of the type bar.
- 20 25 5. In a typewriting machine, the combination of a series of type bars which strike at a common center, a single center guide roller, and guiding means on each type bar which co-act with said single guide roller to prevent lateral deflection of each type bar in opposite directions.
- 30 35 6. In a typewriting machine, the combination of a series of type bars which strike at a common center, a single center guide roller, and guiding means on each type bar which co-act and interlock with said guide roller and prevent longitudinal as well as lateral deflection of each type bar.
- 40 45 7. In a typewriting machine, the combination of a series of type bars which strike a common center, a grooved center guide roller, and guiding means on each type bar which are received in the groove of said guide roller and co-act with the roller to guide the bar.
- 50 55 8. In a typewriting machine, the combination of a series of type bars which strike a common center, a center guide roller, and guiding means on each type bar which co-act with said guide roller on opposite sides thereof.
9. In a typewriting machine, the combination of a series of type bars which strike a common center, a center guide roller mounted to turn on a fixed axis, and guiding means on each type bar which co-act with said guide roller on opposite sides of said fixed axis.
10. In a typewriting machine, the combination of a series of type bars which strike a common center, a pivoted center guide roller the pivotal axis of which extends transversely of each type bar when the latter is in the printing position, and guiding means on each type bar which co-act on op-
- posite sides of the bar with the center guide roller.
11. In a typewriting machine, the combination of a series of type bars which strike a common center, a pivoted center guide roller the pivotal axis of which extends transversely of each type bar when the latter is in the printing position, and guiding means on each type bar which co-act on opposite sides of the bar with the center guide roller and which also co-act with the roller on opposite sides of the pivotal center thereof in order to prevent longitudinal as well as lateral deflection of each bar. 70 75
12. In a typewriting machine, the combination of a series of type bars which strike a common center, and a pivoted grooved center guide roller, the pivotal axis of which extends transversely of each type bar when the latter is in the printing position, each type bar being slotted transversely to receive the grooved portion of the roller and having guide surfaces which co-act therewith. 80 85
13. In a typewriting machine, the combination of a series of type bars which strike a common center, a center guide roller having a substantially V-shaped groove therein, and a guiding surface on each type bar which is received in said groove and co-acts with the guide roller. 90 95
14. In a typewriting machine, the combination of a series of type bars which strike a common center, a center guide roller having a groove therein with side walls which are inclined to the axis of said roller, and guiding means on each type bar which co-act with said inclined walls of the center guide. 100
15. In a typewriting machine, the combination of a series of type bars which strike a common center, a center guide having oppositely inclined rolling guiding surfaces which co-act with each type bar on opposite sides thereof, and oppositely inclined guiding surfaces on opposite sides of each type bar which co-act with the inclined rolling surfaces of the center guide. 105 110
16. In a typewriting machine, the combination of a series of type bars which strike at a common center, guiding means which guide and prevent a deflection of each bar in two directions at right angles to each other, said means comprising a center guide near the printing point and having rolling guiding surfaces with which each type bar co-acts with an interlocking engagement as it approaches the printing position thus preventing a longitudinal as well as a lateral deflection of each type bar, and means for effecting a relative adjustment between the bearings of the rolling guiding surfaces of the center guide. 115 120
17. In a typewriting machine, the combination of a series of type bars which strike at a common center, guiding means which 125

guide and prevent a deflection of each bar in two directions at right angles to each other, said means comprising a center guide near the printing point and having rolling 5 guiding surfaces with which each type bar co-acts with an interlocking engagement as it approaches the printing position thus preventing a longitudinal as well as a lateral deflection of each type bar, the guiding 10 surface on each bar being formed on an arc the center of which corresponds to the pivot of the type bar, and means for effecting a relative adjustment between the bearings of the rolling guiding surfaces of the center 15 guide.

18. In a typewriting machine, the combination of a series of type bars which strike at a common center and converge near the printing point, said bars as they approach 20 the sides of the system being bent laterally at the ends thereof beyond the point where they converge so that the end portions of all of the bars may be brought to the same plane, guiding means which guide and prevent deflection of each bar in two directions at right angles to each other, said means comprising a center guide having rolling 25 guiding surfaces which co-act and interlock with those portions of the type bars which are brought to the same plane and prevent a longitudinal as well as a lateral deflection of the type carrying end portion of each 30 bar, and means for effecting a relative adjustment between the bearings of said rolling 35 surfaces.

19. In a typewriting machine, the combination of a series of type bars which strike at a common center and converge near the printing point, said bars as they approach 40 the sides of the system being bent laterally at the ends thereof and beyond the point where they converge so that the end portions of all of the bars may be brought to the same plane, guiding means which guide and prevent deflection of each bar in two directions at right angles to each other, said means comprising a center guide having rolling 45 guiding surfaces which co-act and interlock with those portions of the type bars which are brought to the same plane and prevent a longitudinal as well as a lateral deflection of the type carrying end portion of each 50 bar, the guiding surface on each bar being formed on an arc the center of which corresponds to the pivot of the type bar, and means for effecting a relative adjustment between the bearings for the rolling guiding 55 surfaces of the center guide.

20. In a typewriting machine, the combination of a series of type bars which strike 60 at a common center, a single center guide roller, guiding means on each type bar which co-act with said single guide roller to prevent lateral deflection of each type bar in

opposite directions, and means for effecting 65 a relative adjustment between bearings of said guide roller.

21. In a typewriting machine, the combination of a series of type bars which strike at a common center, a single center guide 70 roller, and guiding means on each type bar which co-act and interlock with said guide roller and prevent longitudinal as well as lateral deflection of each type bar, and means for effecting a relative adjustment be- 75 tween the bearings of said guide roller.

22. In a typewriting machine, the combination of a series of type bars which strike a common center, a grooved center 80 guide roller, guiding means on each type bar which are received in the groove of said guide roller and co-act with the roller to guide the bar, and adjusting means for the bearings of said roller.

23. In a typewriting machine, the combination of a series of type bars which strike a common center, a center guide roller, guiding means on each type bar which co-act with said guide roller on opposite sides thereof, and adjusting means for the bear- 85 90 95 ings of said guide roller.

24. In a typewriting machine, the combination of a series of type bars which strike a common center, a pivoted center guide roller the pivotal axis of which extends 95 transversely of each type bar when the latter is in the printing position, guiding means on each type bar which co-act on opposite sides 100 of the bar with the center guide roller, and means for effecting a relative adjustment between the pivot bearings of said guide roller.

25. In a typewriting machine, the combination of a series of type bars which strike a common center, a pivoted grooved center 105 guide roller, the pivotal axis of which extends transversely of each type bar when the latter is in the printing position, each type bar being slotted transversely to receive the grooved portion of the roller and having 110 guide surfaces which co-act therewith, and adjustable means for the bearings of said guide roller.

26. In a typewriting machine, the combination of a series of type bars which strike a common center, a center guide having op- 115 positely inclined rolling guiding surfaces which co-act with each type bar on opposite sides thereof, oppositely inclined guiding surfaces on opposite sides of each type bar which co-act with the inclined rolling surfaces of the center guide, and adjustable 120 means for said center guide.

27. In a typewriting machine, the combination of a series of type bars which strike a common center, a pivoted center guide 125 roller with which said type bars co-act to direct them to the printing point, a two-part bearing for said guide roller, and means for

effecting a relative adjustment between the members of said two-part bearing.

28. In a typewriting machine, the combination of a series of type bars which strike 5 a common center, a pivoted center guide roller with which said type bars co-act to direct them to the printing point, a two-part bearing that receives the pivots at the ends of said guide roller, and means for effecting 10 a relative adjustment between the two members of said two-part bearing.

29. In a typewriting machine, the combination of a series of type bars which strike a common center, a pivoted center guide 15 roller with which said type bars co-act to direct them to the printing point, a two-part bearing that receives the pivots at the ends of said guide roller, means for enabling one member of the two-part bearing to rock on 20 the other and thus effect a relative adjustment between the two members, and means for holding said members in the relative position to which they may be adjusted.

30. A type bar center guide roller, a two- 25 part bearing for said roller, means for enabling one part of the bearing to move relatively to the other, a screw which holds one member to the other, and adjusting screws one for effecting a relative adjustment be- 30 tween the members in one direction and the other for effecting a relative adjustment between the members in the opposite direction.

31. A type bar center guide roller provided with pivot bearings at the ends thereof, 35 two relatively adjustable arms which support said pivot bearings, and means for effecting a relative adjustment between said arms.

32. A type bar center guide roller, two 40 relatively adjustable arms which support said roller, and means for effecting a relative adjustment between said arms.

33. In a typewriting and like machine, the combination of a series of converging 45 type carriers which strike at a common printing center, a type block on each type carrier, a center guide, and guiding portions on each type carrier which coact with said center guide beyond the point of conver- 50 gence of the type carriers; the guiding portions of the different type carriers having

surface conformations which vary in the different type carriers.

34. In a typewriting and like machine the combination of a series of type carriers 55 which strike at a common printing center, a center guide, and co-acting guide surfaces on each type carrier which co-act with said center guide, the guide surfaces on each type carrier being of a different formation 60 from the guide surfaces on any of the other type carriers, the co-acting guide surfaces on the center guide and on each type bar interlocking to prevent a deflection of the type carrier in two directions at right angles 65 to each other.

35. In a typewriting and like machine the combination of a series of type bars which strike a common center and each of which has a slot formed therein, and a center guide 70 having a rolling guide surface which is received in each of said slots.

36. In a typewriting and like machine, the combination of a series of type bars which strike a common center and each of 75 which has a slot formed in the forward edge thereof and which extends throughout the thickness of the bar, and a center guide having rolling guide surfaces which are received in the slot in each bar and co-act with 80 the walls thereof.

37. The combination of a center guide located near the printing point and having oppositely inclined walls, and a series of type bars which co-act with said guide, each 85 type bar having a slotted portion near the type carrying end thereof, the edges of said slotted portion of each type bar being inclined to match the inclined walls of the guide and to coact therewith on opposite 90 sides before the type bar reaches the printing position, thus guiding the bar and preventing its deflection in two directions at right angles to each other.

Signed at Syracuse, in the county of 95 Onondaga and State of New York, this 19 day of March, A. D. 1918.

HERBERT E. BRIDGWATER.
